UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

TYPE-DIE.

1,102,398.

Specification of Letters Patent.

Patented July 7, 1914.

Application filed June 18, 1913. Serial No. 774,317.

To all whom it may concern:

Be it known that I, JOSEPH S. DUNCAN, a citizen of the United States, residing at Chicago, in the county of Cook and State 5 of Illinois, have invented certain new and useful Improvements in Type-Dies, of which the following is a specification.

This invention relates in general to dies adapted for use in connection with suitable 10 punches for producing printing characters in relief on sheet metal blanks or plates and has more particular reference to dies of the general character disclosed in my prior U. S. Letters Patent No. 1,048,460 and 15 1,048,461, issued December 24, 1912.

In my companion application, Serial No. 773,430, filed June 18, 1913, I have disclosed a die provided at its operating end with a centrally disposed character-forming element and a ledge extending laterally from said element to the side of the die, this ledge being adapted to overlie a previously formed printing character during the operation of the die to prevent the previously 20 formed character from becoming distorted or displaced during the formation of the next succeeding character.

My present invention aims to produce a die having a ledge of maximum width 30 which will present a large area and be especially efficacious in preventing distortion or displacement of a previously formed printing character; and with this end in view, the character forming element in my present die, 35 is disposed adjacent to one vertical side face of the die body.

Another object of the invention is to produce a die which will remove any roughness or irregularity from the faces of the printing 40 characters and reduce all the printing characters to a uniform height with their printing faces disposed in a common plane, this object being effected in the present instance by forming the face of the ledge nearer to the extremity of the die than the bottom of the character-forming depression 45 so that the ledge face will engage with and depress the face of the next preceding character at each operation.

50 My invention will be best understood by reference to the following description when considered in connection with the accompanying drawings, by reference to which, it will be observed that Figure 1 is a fragmentary side elevation of a printing device

showing a punch and my novel die in co-operative relation therewith; Fig. 2 is a longitudinal sectional view taken substantially on the line 2—2 of Fig. 3; Fig. 3 is a transverse sectional view taken substantially on the line 3—3 of Fig. 2; Fig. 4 is a sectional view on the line 4—4 of Fig. 3; Fig. 5 is an end view of my improved die; Fig. 6 is a perspective view of the die shown in Fig. 5; and Fig. 7 shows a slightly 60 different form of die embodying my invention.

By reference to the drawings, it will be observed that in the formation of printing characters, such as shown on the drawings, 70 I employ a punch 10 of suitable construction to coöperate with my improved die 11 for the purpose of stamping up the printing characters 12 on one face of a sheet metal blank 13. The punch 10 is provided at its 75 operating end with a suitable elevated character-forming face 14 surrounded, in the embodiment illustrated, by a flat shoulder 15.

The die 11 which coöperates with the 80 punch 10, is provided at its operating end with a channel or recess extending transversely across the end of the die and forming at its bottom a flat face 16, the side walls of the channel providing lips 17 and 18 85 which project longitudinally of the die beyond the face 16. The character-forming depression 19, complementary to the character-forming elevation 14 on the punch, is formed on the face 17 between the lips 18 and 19. It will be observed that the face 16 is disposed normal to and intersects the side face 21 of the die and that the character-forming depression 19 is positioned on the operating end of the die adjacent to the side 90 face 21, so that the depression is disposed laterally with respect to the longitudinal axis of the die. Adjacent to the inner edge of the character-forming depression, the metal of the die is cut away or otherwise 100 formed to provide a ledge 22, depressed relatively to the face 16 and extending parallel therewith to the opposite side of the die. The face of the ledge 22 is depressed relatively to the face 16 a distance slightly less 105 than the depth of the character-forming depression therein, the ledge being consequently located below the extremities of the lips 18 and 19, a distance slightly less than the height of the printing face of the charac- 110

ters above the plane of the plate from which the characters are formed. The printing face of each character is therefore depressed by the ledge an amount equal to the depth of the character-forming depression below the ledge, during the formation of each succeeding character, thereby flattening and removing any irregularities in the printing faces of the characters. The ledge extends 10 at least from the lip 18 to the lip 19, and for convenience of manufacture, it preferably extends through the lips, as best shown in Figs. 5 and 6, although, if preferred, the ledge may terminate at the lips as shown in 15 Fig. 7. In order that the body of the die may not contact with adjacent lines of printing characters during the operation of the die, the outer faces of the lips 17 and 18 are beveled, as indicated by reference characters 20 23 and 24 respectively; the lip 17 being preferably beveled more than the lip 18 to provide sufficient clearance between the die and an adjacent line of printing characters, as shown in Fig. 3.

25 When the punch and die are brought into coöperative relation, the metal of the plate at the top and bottom of the character is maintained in its normal plane by the lips 17 and 18, the edges of which, when the punch 30 and die are forced together, are spaced from the shoulder 16 of the punch, a distance sufficient to retain the metal at the top and bottom of the character in its original plane. During the formation of the character, the 35 metal at the left of the character is bent upwardly from its original plane, as best shown in Fig. 2, and the metal at the right of the character, between the previously formed character and the character being 40 formed, is elevated or drawn upwardly some little distance above its original position. The metal, which forms the printing character itself, is forced upwardly into the character-forming depression of the die by the 45 elevated character-forming face 14 of the punch which is preferably slightly larger in cross-sectional area than the character-forming depression. The displacement of the metal at the right of the character being 50 formed has a tendency to displace the previously formed character from its proper position by tilting or otherwise, so that its printing face will not lie in a plane parallel with the plane of the face of the plate, such dis- 55 placement being particularly noticeable when the characters are formed in close juxtaposition. To obviate this displacement of the previously formed character, the ledge 22, as will be observed by reference to Figs. 60 2 and 4, is constructed and positioned to provide a gage or abutment adapted to overlie and, upon actuation of the die, depress the face of the previously formed character sufficiently to relieve it of surface irregularities and reduce the face to a common

printing plane. By positioning the character-forming depression adjacent to one edge of the operating end of the die, a ledge of maximum width may be formed which will overlie approximately the entire printing 70 face of a previously formed character of maximum width, thereby positively engaging and positioning the entire printing face of the printing character. It will be manifest, therefore, that the printing faces of all 75 the characters in a line will be disposed in a common plane so as to produce equally clear and distinct impressions.

While I have shown and described the die adapted to produce the letter "M," it will 80 be obvious that the operating face of the die may be supplied with any desired character-forming depression, and that as the width of the character decreases, the width of the adjacent ledge may be correspondingly increased. In any event, a ledge of maximum width is secured by reason of the fact that the character-forming depression is positioned closely adjacent to one side of the die.

I claim:

1. A die for forming printing characters in a metal plate, comprising a body provided at one end with a character-forming element disposed adjacent to one side of the body, and a ledge disposed adjacent to the opposite side of the body in position to overlie a previously formed character.

2. A die for forming printing characters in a metal plate, provided at its operating end with a character-forming element positioned adjacent to one vertical side of the die, lips projecting longitudinally of the die at the top and bottom of said character-forming element, and a ledge extending from the opposite vertical side of the die toward 100 said character-forming element.

3. A die for forming printing characters in a metal plate, comprising a body having at its operating end a flat face disposed adjacent to one side of the body, said face being provided with a character-forming depression, and a ledge depressed relatively to said face and extending from said face to the opposite side of the body.

4. A die for forming printing characters in a metal plate, having parallel side walls at its operating end, a character-forming element located adjacent to one of said walls on the operating end of the die, the walls of the die at the top and bottom of said character-forming element being extended longitudinally to provide lips, and a ledge disposed between said character-forming element and the other parallel wall of the die to overlie previously formed characters during successive operations of the die.

5. A die for forming printing characters in a metal plate, provided at its operating end with a character-forming element positioned laterally with respect to the central 130

axis of the die, and having a ledge extending on the opposite side of said central axis from the character-forming element.

6. A die for forming printing characters in a metal plate, provided at its operating end with a flat face disposed normal to the adjacent longitudinal face of the die, said flat face being provided with a character-forming depression, a ledge depressed relatively to said flat face and extending from said face and parallel therewith to the opposite vertical face of the die, and lips extending longitudinally of the die outwardly beyond said flat face at the top and bottom of said character-forming depression.

7. A die for forming printing characters in a metal plate, provided at its operating end with a flat face having a character-forming depression formed therein, and a ledge depressed relatively to said face a distance less than the depth of said depression, said ledge extending from said face to the opposite side of the die.

8. A die for forming printing characters in a metal plate, provided at its operating

end with a character-forming depression, and a ledge disposed at one side of said depression, said ledge being nearer the extremity of the die than the bottom of said character-forming depression.

9. A die for forming printing characters in a metal plate having at its operating end a flat face, and a ledge parallel with said face but depressed relatively thereto, said face being provided with a character-forming depression extending into the die below the plane of said ledge.

10. A die for forming printing characters in a metal plate, provided at one end with a character forming element positioned laterally with respect to the longitudinal axis of the die, said die being formed to provide a ledge extending from the opposite side of the die toward the character forming element and positioned to overlie a previously formed printing character.

JOSEPH S. DUNCAN.
